(57) **CLAIM**

The ornamental design for a flip mount, as shown and described.

DESCRIPTION

FIG. 1 is an isometric view of a flip mount showing the new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The broken lines depict portions of the flip mount that form no part of the claimed design.
